UNITED STATES PATENT OFFICE

2,538,577

SPARKLESS CAMERA SHUTTER AND FLASH
TUBE SYNCHRONIZER

Clyde W. McCarty, Lynn, Mass., assignor to General Electric Company, a corporation of New York

Application May 8, 1948, Serial No. 25,863

1 Claim. (CL 95—11.5)

1

This invention relates to electric discharge devices and more particularly to a new and improved apparatus for triggering so-called flash tubes.

Heretofore, there have been devised various excitation circuits for controlling the conductivity of flash lamps. However, these circuits, embodying switches which employ current-carrying contacts, could not be used in an explosive atmosphere, such as exists in a hospital operating room, for instance. Thus, a sparkless apparatus for triggering a flash lamp is needed for applications of this nature.

An object of my invention is to provide a new and improved igniter-excitation apparatus for an electric discharge device.

Another object of my invention is to provide a new and improved sparkless apparatus for triggering a photographic flash lamp of the gaseous conduction type.

A further object of my invention is to provide a new and improved apparatus for triggering a flash lamp, which apparatus employs a magnet secured to a shutter of a camera for actuating a control valve which in turn triggers the flash lamp.

Further features and advantages of my invention will appear from the following description of species thereof.

For a better understanding of my invention reference may be had to the following description taken in connection with the accompanying drawing and its scope will be pointed out in the appended claim. The drawing is a diagrammatic view of an electric discharge device and a triggering device therefor incorporating my invention.

Referring to the drawing, I have there illustrated one embodiment of my invention as applied to an electric discharge lamp 1. Lamp 1 may be of the cold cathode gas or mercury vapor type which has come into general use, particularly in photographic applications, mainly because of its ability to emit high intensity illumination and to reach full intensity almost instantaneously. In addition, lamp 1 is usually designed to furnish illumination only during very short increments of time and to furnish such a "flash" at any chosen instant and at any chosen repetition rate.

Lamp 1 usually comprises a cathode 2 and an anode 3 within a gas-tight vitreous envelope 4 containing a suitable gas such as xenon or argon or mercury in liquid or vapor form. Electrical discharge does not occur when normal anode-to-cathode voltage is applied, since ionization remains sufficiently low to prevent breakdown

2

through the enclosed gas. However, ionization may be increased sufficiently to cause discharge by sharply increasing the voltage gradient in the gas, or a portion thereof. Such a voltage gradient increase causes increased ionization since displacement current or condenser charging current in the dielectric consisting of the enclosed gas results, which current causes additional ionization. This may be accomplished by applying a voltage pulse between anode 3 and cathode 2. Discharge in lamp 1 continues as long as the anode-to-cathode voltage exceeds a critical value below which current flow stops. Thus, a source of anode-to-cathode voltage capable of supplying energy, and of sharply drooping load characteristic, must be provided if "flashes" of short duration are desired. Further, a large triggering voltage must be supplied at the instant illumination is desired.

20 In accordance with my invention, lamp 1 is connected across a discharge circuit 5, 5' which may be energized from a 118 volt, 60 cycle source of current through the primary winding 6 of a transformer 7. A manual make-and-break control switch 8 may be used to connect transformer 7 to the source of current. A secondary winding 9 of transformer 7 is connected through a rectifier 10, and a charging impedance 11 which may be constituted of inductance or resistance, or both, to a capacitance 12. A rectified or direct current source is thus provided for charging the capacitance 12 to a voltage, for example, of 2000 volts. A bleeder resistance 13 is connected across capacitance 12, which in turn is in parallel with lamp 1. A control valve or trigger tube 14 may be connected to terminals 15 and 16 of the bleeder resistance 13, so as to be supplied with a desirable operating voltage therefrom. The trigger tube 14 may be a thyratron which may comprise an evacuated glass envelope 17 filled with a suitable gas, such as neon, and is provided with a plurality of electrodes, namely a cathode 18, an anode or plate 19, a control grid 20, and a shield grid 21. To terminals 15 and 16 of bleeder 13 there is also connected, in series with a capacitance 22, a primary winding 23 of a voltage transformer 24. A secondary winding 25 of transformer 24 is connected to a triggering coil 26 wound around envelope 4 of lamp 1. Control grid 20 is connected through a resistance 27 to a wire coil 28. A magnet 29 which, for example, may be a bar magnet three-eighths of an inch in diameter, mounted on a flap or door type shutter 30 of a camera 31, is provided to actuate the trigger tube 14 upon opening of the camera shutter 30.

Coil 28 is mounted in the path of movement of magnet 29 so that upon opening of shutter 30 of camera 31 the magnet will move into coil 28 which is located near the end of travel of magnet 29. Magnet 29 in turn induces a voltage impulse in coil 28 which is sufficient to cause the trigger tube or thyratron 14 to fire, the thyratron grid voltage being adjusted so that the voltage generated in coil 28 by magnet 29 is sufficient to cause tube 14 to conduct. The condenser 22 then discharges through the condenser discharge circuit comprising the trigger tube 14 and the primary winding 23 of transformer 24. The resulting high-voltage surge of the secondary winding 25 of transformer 24 is applied to the triggering coil 26 which is wound around the envelope 4 of lamp 1. This causes the gas in the lamp 1 to ionize, permitting the condenser 12 to discharge through lamp 1 between its electrodes, producing a very brilliant flash of short duration.

Thus, when the entire installation is energized by closing switch 8, condenser 12 becomes charged from the direct current source supplied by the rectifier tube 10, trigger tube 14 being non-conductive. The source of direct current in addition charges the condenser 22 at the same time. Any time after the voltage across condensers 12 and 22 has reached its maximum value, the shutter 30 of camera 31 may be opened and an induced voltage is generated in coil 28 by the action of magnet 29 entering into coil 28. This induced voltage in coil 28 raises the potential of the control grid 20 until the breakdown voltage between control grid 20 and cathode 18 is exceeded and the trigger tube 14 becomes conductive. The condenser 22, as heretofore mentioned, then discharges through the condenser-discharge circuit comprising trigger tube 14 and the primary winding 23 of transformer 24. The resulting high-voltage surge of the secondary winding 25 of transformer 24 is applied to the triggering coil 26 of lamp 1. This causes the gas in lamp 1 to ionize, permitting the condenser 12 to discharge through the lamp 1, and thus produce a very brilliant flash of short duration. When the con-

denser 12 is fully discharged, the discharge lamp 1 promptly extinguishes and the cycle is ready for repetition.

When the condenser 12 is fully discharged the voltage across the bleeder 13 is approximately zero and thus prevents condenser 22 from charging and, in turn, permits trigger tube 14 to de-ionize. The time taken for a complete cycle of operation is very brief and the apparatus is again ready for a repetition cycle.

What I claim as new and desire to secure by Letters Patent of the United States is:

In combination with a gaseous electric discharge lamp having a plurality of electrodes therein, a current supply circuit, a discharge circuit connected to said electrodes across said supply circuit to effect a flash-producing discharge through said lamp, a starting circuit for supplying a triggering voltage to said lamp at a point on said lamp intermediate said electrodes and comprising a voltage step-up means and a grid controlled electric valve control means connected to control current flow through said step-up means, a camera, a normally closed flap type shutter mounted on said camera, a magnet mounted on said shutter, and a wire induction coil mounted in the path of movement of said magnet near the end of the path of travel thereof and connected to supply a potential to the grid of said control means sufficient to render the control means conductive and permit current flow through said step-up means.
